SHAVING IMPLEMENT

John Bruecker, Chicago, Ill.

Application February 2, 1940, Serial No. 316,990

19 Claims. (Cl. 30—43)

This invention relates to shaving implements and has special reference to a so-called dry shaver having a novel and improved cutting head.

An important object of the invention is the provision of a shaver having a comb structure of novel and more efficient shape characteristics such that more uniform and closer shaving results may be obtained. In this connection one of the features of my invention is the provision of an elongated comb which is curved both lengthwise and crosswise. The two way curvature of this comparatively long and narrow cutting area is particularly beneficial in promoting close shaving.

Another object of the invention is the provision of a shaver having a comb and cutter so arranged as to combine efficient cutting of both long and short hair whereby to produce greater speed in the shaving operation even when the beard has become considerably longer than the usual close shaved beard, and whereby to avoid the presence of isolated long hair after the completion of the shaving operation. In this connection one of the features of my invention is the provision of a novel form of clipper teeth having characteristics which promote improved cutting of long hairs, and particularly adapted for combination with means for close shaving.

Another object of the invention is the provision of a comb structure which has greater strength, can be manufactured with greater uniformity, and can be caused to retain its shape characteristics to a greater exactitude than with prior comb structures.

Another object is to provide an improved comb structure in the nature of a unit having an elongated close shaving portion arched longitudinally and transversely and preferably including at one or both sides an open end row of clipping teeth conforming with the longitudinal and transverse curvature of the close shaving portion.

Another object is to provide a shaver having an improved form of cutter and cutter support.

A further object is to improve the construction and method of assembly of the comb structure with the view to promoting economy in cost of manufacture considering the high degree of precision desired.

Other objects and advantages will appear from the following description and the accompanying drawings, in which

Figure 1 is a side elevation of a shaver embodying my invention, approximately full size;

Fig. 2 is an elevation taken at right angles to Figure 1 showing the shaver with the casing cover removed;

Fig. 3 is a fragmentary side view partly in section and enlarged approximately four times Figure 1, showing the cutter head of Fig. 2;

Fig. 4 is an end view of the cutter head showing the outer face of the comb;

Figs. 5, 6 and 7 are fragmentary face views showing alternative forms of openings in the comb, and alternative ways in which the comb may be supported;

Fig. 8 is a section through the center of the cutter head substantially along the line 3—3 of Fig. 4;

Fig. 9 is a section on the line 9—9 of Fig. 2, on the same scale as Fig. 8;

Fig. 10 is an enlarged fragmentary perspective view of a comb side member showing one of the clipping teeth;

Fig. 11 is a side view of a shaver with the cover removed showing a second embodiment of the invention, approximately twice full size;

Fig. 12 is a section on the line 12—12 of Fig. 11;

Fig. 13 is an end view of the cutter head shown in Fig. 11, showing the outer face of the comb and its support, the scale being approximately four times full size;

Fig. 14 is a side view of the cutter head shown in Fig. 13;

Fig. 15 is a section on the line 15—15 of Fig. 14;

Fig. 16 is a perspective view of one of the comb sections of the embodiment shown in Figs. 11 to 15;

Fig. 17 is a fragmentary view showing a modified arrangement of the shaving openings of the comb structure;

Fig. 18 is a plan view of the comb blank of another embodiment of my invention, approximately four times full size;

Fig. 19 is a side elevation of the comb shown in Fig. 18, formed to shape;

Fig. 20 is a section taken on the line 20—20 of Fig. 19;

Fig. 21 is a plan view of another modification of my invention, showing a comb part formed of a single piece of metal, approximately four times full size;

Fig. 22 is a fragmentary side view of shaver parts showing the application thereto of the comb part shown in Fig. 21;

Fig. 23 is an enlarged detail section through the comb and truss structure of Figs. 21 and 22,

as taken substantially on the line 23—23 of Fig. 21, showing a means of attaching the comb member to the truss structure; and

Fig. 24 is a fragmentary cross section through the shaver structure shown in Fig. 22.

The invention contemplates novel features in a shaver head and is directed more particularly to the shape characteristics of the comb structure and of the cutter. The cutter may be driven by any desired type of motor, one type of motor being shown in connection with the embodiment of Figs. 1 to 10 inclusive, and another type of motor drive being shown in connection with the embodiment of Figs. 11 to 17.

Referring first to the embodiment shown in Figs. 1 to 10, the numeral 18 designates generally the handle of the shaver made in the form of a housing for the purpose of enclosing the motor. The handle has a body member 19 and a cover 21 secured to the body by means of screws 22 and 23, in this instance arranged on the longitudinal center line. Secured within the handle is an impulse motor having the usual coil 24, field pole pieces 25, and armature 26. The armature 26 is supported in spaced plates 27 and carries a crank pin 28 arranged to drive the cutter in a manner presently to be described. Electric current is supplied to the motor through terminal posts 29 located in one end of the handle in the usual fashion.

Carried in the opposite end of the handle is a shaver head assembly designated generally by the numeral 31 which in this instance includes a frame in the form of a box-like structure having a back wall 32 provided with annularly disposed flanges on three sides forming a bottom wall 33 and side walls 34, a plate 35 being secured to the free edges of the bottom and side walls as shown in Figs. 8 and 9 to complete the box-like frame structure. The frame 31 is held in position in the handle by means of screws 36 and 37 which also serve to hold the cover 35 in position against the walls 33 and 34. One or more screws 38 act between the wall 32 in the case to further retain the frame in position.

A comb unit designated generally by the numeral 39 is also held in the frame 31 by means of the screws 36 and 37, as will be apparent from Figs. 3 and 9 and may be removed as a unit from the frame and from the shaver by removal of the screws 36 and 37. This comb unit includes a truss, a supporting structure and a skin-engaging structure seated thereover, the truss structure in this instance comprising three ribs designated generally by the numerals 41, 42 and 43 (Fig. 4), the ribs having central arched supporting portions 44, 45 and 46 depending legs 47, 48 and 49 at opposed ends thereof, each of these legs having an opening 51 adjacent the lower end thereof. Tubular rivets 52 pass through the openings 51 of the legs, one on each of the screws 36 and 37. Each of these rivets carries spacer sleeves 54 disposed between the legs 47 and 48 and the legs 48 and 49 respectively, for the purpose of spacing the distance between the ribs (Fig. 9). The rivets also carry end sleeves 55 and 56 at opposite ends thereof against which the rivets are peened, these end sleeves having annular flanges 57 and 58 providing annular grooves 59 and 61 for a purpose presently to be described. The skin-engaging structure comprises a central close shaving area designated generally by the numeral 62 and marginal areas indicated by the numerals 63 and 64. In this instance the central area comprises a strip of thin sheet metal of substantially greater length

than width having substantially parallel side edges 65 and 66 intermediate its ends and having end portions 67 and 68 of somewhat greater width, the width of the strip being such that the side edges 65 and 66 can seat substantially along the center of the ribs 41 and 43 when the strip is seated thereon as shown. The strip is secured to the truss structure by means which will not cause distortion of the very thin strip. In the present instance I employ wire retaining members 69 and 71 extending transversely of the strip at the widened portions 66 and 67, passing through spaced openings in the strip, and depending therefrom as best shown in Fig. 3. The depending ends of said wire members have loops 72 and 73 which pass around the end sleeves 55 and 56 and seat in the annular grooves 59 and 61, thereby drawing the strip taut against the upper edges of the ribs 41, 42 and 43 without distortion.

The marginal areas 63 and 64 include, in this instance, marginal portions of similar structure, each having depending parallelly disposed side portions 74 and top portions 75 having edges shaped to seat in edge abutment against the edges 65 and 66 of the central strip, as best shown in Figs. 4 and 8. The side portions are secured against the legs 47 and 48 of the ribs 41 and 43 by means of screws 76 and 77, spacer sleeves 78 and 79 maintaining the side portions in proper spaced relation to the ribs and maintaining the edges of the top portions 75 in abutment with the edges 65 and 66 and in seated relationship against the upper edges of the ribs 41 and 43. The side portions 74 are curved to conform with the lengthwise and crosswise curvature of the central portion 62 above described, and the marginal sides are formed in the nature of a cyma curve, as shown at 81 at the junction between the side portions and the top so as to overhang or project over the side portions as best shown in Figs. 8, 9 and 10. The inner edges of the top portion 75 are rounded slightly as shown at 82 so as to merge with the outer surface of the central area. The marginal portions are preferably formed from sheet metal and suitably hardened after their formation to provide the desired edge retaining properties and to withstand the wear occasioned by the shearing action presently to be described. In this particular instance said portions are approximately ten-thousandths of an inch in thickness. The top portion of the marginal area is provided with spaced U-shaped cuts as shown at 83 (Fig. 10) which cuts extend downward beyond the overhanging portions 81 and provide outwardly disposed teeth 84, which teeth terminate at their free end slightly beyond the plane of the sides 74 and provide shearing edges along their sides. Shearing edges are also formed on opposed sides of the slot 83 in the areas designated by the numerals 85 and 86 so that each of the U-shaped slots functions to provide four shearing edges. These slots are spaced longitudinally of the marginal areas 63 and 64 as best shown in Fig. 4 to provide clipping action on each side of the comb extending throughout substantially the length thereof. The intermediate portions between the slots such as shown at 87 act as guards to limit the approach of the teeth to the skin of the user. The projecting teeth 84, while protected by the adjacent guards 87, serve to effectively engage beneath and pick up long hairs. This function is facilitated by the relatively wide mouth opposite the end of each tooth 84 and the narrow slot-like areas 85—86.

opening therefrom, with the result that long hairs may enter the slotted area either lengthwise or crosswise with respect to the cutting tooth 84 and be readily engaged beneath the tooth or across the cutting edges at the outer side of the slotted areas 85—86.

The strip forming the central area 62 is preferably formed of soft sheet steel of thin cross section in the region of three thousandths of an inch or less thickness. After having been formed to the desired shape the strip is suitably hardened to provide proper edge-holding properties for the cutting edges at the inner end of the hair-receiving openings and to withstand the shearing action. This central area is provided with a plurality of hair-receiving openings designated in Fig. 4 by the numeral 86. The specific size, shape and arrangement of these openings may vary to a considerable degree, the size of the openings depending to some extent on the thickness of the comb and its degree of curvature. For instance, in Figs. 1 to 4 I have shown the openings 86 in the form of slots which extend diagonally across the area in longitudinally spaced relation. In Figs. 5, 6 and 7 I have shown alternative forms, the form shown in Fig. 5 having two rows of spaced slots, as indicated at 89 and 91, the slots being spaced on opposite sides of the rib 42 and the area being solid in the space over the rib. In Fig. 6 I have shown a structure which includes three rows of slots as shown at 92, 93 and 94, and wherein the truss structure employs four ribs instead of the three ribs heretofore described for lending additional support across the width of the central strip. In Fig. 7 I have shown a central strip which is provided with a plurality of circular openings as shown at 95, the openings being spaced longitudinally and laterally of the strip. In each case the openings are adapted to receive the short hair of the beard in such a way that the hair projects through the opening in position to be severed by joint action of the strip and a cutter, which will presently be described, without letting the skin through to cause irritation or cutting. These openings are of a kind adapted for close shaving. It will be understood that the number of ribs provided in the truss structure will vary depending upon the width of the central strip and the amount of support required in this area.

The portion of the structure formed by the central area 62 and the marginal areas 63 and 64, which I have designated the skin-engaging portion of the comb, is arched in two directions at right angles to each other. In other words, this skin-engaging portion is arched longitudinally of the comb as shown in Fig. 3 and is likewise arched transversely as shown in Fig. 8, the central strip and the top portions 75 being formed individually in such manner that when positioned on the truss structure the composite top surface thus formed produces the arched skin-engaging portion, and this shape characteristic forms an important part of the invention for the reason that by so forming the strip an extremely thin section may be used having substantially greater rigidity than is the case with a flat sheet. Another advantage is the fact that this curved surface greatly facilitates the shaving operation for the reason that when pressed against the skin it imparts curvature thereto tending to distribute the pressure and to cause the hair to enter the openings at the proper angle, and facilitates the entry of the hair into the openings. Another advantage is that by

reason of its double curvature and elongated form it is better adapted to follow the different shapes of the face and to work into hollow portions. It will also be noted that the marginal areas 63 and 64 are formed of metal of substantially greater thickness than that of the central area 62 so that the marginal areas have materially greater strength and rigidity to withstand the greater forces occasioned by the clipping action, as distinguished from the close shaving action, and likewise to prevent bending and breaking of the teeth 84 out of their normal and true position due to mechanical damage.

In the preferred embodiment of my invention a flat cutter blade is used in accordance with the principle covered in my Patent No. 2,081,694 granted May 25, 1937. This blade coacts with the comb portions 62 for close shaving and the portions 63 and 64 for clipping long hairs. Any suitable or preferred means may be employed for oscillating the cutter blade at a high speed. The means used in the present embodiment are as follows:

Positioned in the walls 32 and 35 of the frame 31 adjacent to the bottom 33 thereof are bearings 96 and 97 adapted to support a shaft 98 extending through the frame, the shaft having a pin 99 to which is fixedly attached a crank arm 101. This arm is in the form of a fork having legs 102 and 103 shaped to span the crank pin 28, as best shown in Fig. 2, whereby rotation of the crank pin swings the arm from side to side and causes the shaft 98 to oscillate. A sleeve 104 has a press fit on the shaft 98 so as to be fixed thereon, and carries a pair of arms 105 and 106 secured thereon in spaced relation by a spacer block 107 and by end blocks 108 and 109 against which the ends of the sleeve 104 are riveted over to form a rigid permanent structure, as best shown in Fig. 8. The arms 105 and 106 project toward the comb and intermediate their ends are secured together by rivets 111 and a spacing block 112, which spacing block carries a pin 113 serving as a guide for a spring 114. The spring 114 also encircles a stem 115 of a cutter designated generally by the numeral 116. This cutter is formed of sheet metal and has a tongue 117 carrying the pin 115 and seated between the arms 105 and 106 for free movement longitudinally with respect thereto. Beyond the tongue 117 the cutter flares outwardly as shown at 118 to a width slightly less than the distance between the side portions 74 of the comb, the end of the cutter being arcuate, as best shown in Fig. 8, to accurately seat against the inner surface of the skin-engaging portion of the comb. The enlarged portion 118 is received in slots 119 and 121 in the ends of the arms 105 and 106 in such fashion as to be capable of being freely urged against the comb by action of the spring 114, the fit being such as to permit of a minimum amount of lost motion between the cutter and the arms in the direction of movement of the arms but to permit of a limited amount of lateral movement so that the outer end of the cutter may adjust itself laterally to the curvature of the skin-engaging portion of the comb. The cutter has a plurality of slots 122, 123 and 124 for the reception of the central portions 46, 45 and 46 of the ribs, these slots being of such width as to permit of the lateral cutter movement just described.

It will be seen that when the motor is energized the cutter 116 is caused to oscillate, moving across the inner surface of the skin-engaging

portion from end to end thereof, the outer end of the cutter moving in shearing relationship to the shaving openings in the central portion 62 and in shearing relation with the teeth 84 of the marginal areas 63 and 64 to perform a clipping operation. During this oscillation the cutter is urged outwardly by the action of the spring 114 and also by action of centrifugal force due to the angular movement of the cutter. These two forces cause the outer edge of the cutter to hug the inner surface of the comb and thus maintain a shearing pressure between these elements. Furthermore, the cutter is permitted to float laterally with respect to the comb so as to be held in intimate shearing coaction with the comb throughout the shearing stroke. For normal shaving operations on a normal beard the shaver is held so that the central area 62 contacts the skin. The curvature of this area causes the skin to be arched so as to facilitate cutting of the hair very close to the surface of the skin, and this is augmented by the thinness of the central area. Where the beard is slightly longer than normal so that the length of the hair interferes with its entry into the openings of the central area, or when an occasional hair is encountered on the face which either because of its length, its diameter, or the direction in which the hair lies, it is not readily sheared by the central area, the shaver is tilted slightly so as to bring one of the marginal areas 62 and 63 into contact with the skin, whereby either the hair of the longer beard or the individual hair is caused to be clipped by action of the teeth 85 and associated cutting edges spaced along the marginal areas. Also, in the same cutting stroke the close cutting shaving area may be moved across the same hairs for close shaving and thus perform a dual cutting function. As the hair is cut, a certain amount of the severed hair will be carried out at the ends of the comb, but part of it will drop down into the interior of the frame 31. Openings 125 in the walls 32 and 35 of the frame and openings 126 in the handle permit the discharge of this hair outward from the interior of the frame. In order to prevent access of the hair to the motor structure, the junction between the frame and the handle is sealed by packing rings 127 (Fig. 9).

In Figs. 11 to 17 inclusive, I have shown a modified form of the invention having the essential characteristics thereof but in which the specific details vary from that heretofore described. It will be seen from this disclosure that the invention may take a number of specific forms and be made in different ways, but yet incorporate the essential characteristics of the invention. This form of the invention includes a handle and motor housing comprising two interfitting sections designated generally by the numerals 128 and 129 secured together by means of screws 131 and 132. In this instance the handle carries a vibratory type motor designated generally by the numeral 133 adapted to produce reciprocation of an arm 134, this motor and its application to a shaver being subject matter of an application for patent by Ivar Jepson, Ser. No. 324,599 filed March 18, 1910. A plate 135 is secured in the housing portion 128 by means of screws 136 and 137 and has formed thereon upstanding walls 138 and 139 against the free edges of which seat a wall or cover 141 forming a chamber 142 having the upper edge thereof open, as shown in Fig. 12, the cover being secured in position by screws 143. A pin 144 is threaded

into the plate 135 adjacent one edge thereof and carries a bearing 145, the screw passing through the cover 141 for mutual support, gaskets 146 being disposed between the bearing and the plate 135 and the cover 141 respectively, to prevent hair from passing out of the chamber 142 into the lower part of the housing. The walls 138 and 139 likewise have felt gaskets 147 or the like extending from front to rear and seating against the cutter operating lever for sealing the chamber 142 from the motor. The bearing 145 has a depending fork comprising arms 148 disposed on opposite sides of the oscillating arm 134, whereby operation of the motor causes the bearing 145 to oscillate on the pin 144. Extending upwardly from the bearing 145 are spaced arms 149 and 151 having slots 152 and 153 at their upper end for the reception of a cutter designated generally by the numeral 154, the cutter having a depending tongue 155 disposed between the arms 149-151 and a pin 156 adapted to seat in an opening 157 in the bearing 145, the tongue and pin having looseness of movement therein to a certain degree to permit longitudinal movement of the cutter outwardly and to permit a certain amount of lateral movement. A spring 158 acts on the shoulder between the tongue and the pin to normally urge the cutter outward. The cutter is curved outwardly beyond the tongue 155 as shown at 159 and has an arcuate outer edge 161, the cutter being analogous to that of Fig. 8.

A comb unit separately shown in Figs. 13 to 15 inclusive, is seated in the end of the housing in the manner shown in Figs. 11 and 12. This comb includes a truss structure having tubular rivets designated generally by the numerals 162 and 163 upon which is seated spacing sleeves 164 to 167 (Fig. 13), a rib 168 having a central portion 169, and depending arms 171 and 172 are supported on the rivets 162 and 163, the arms having openings for the reception of the rivets and being retained thereon by the spacing blocks as best shown in Fig. 15. The comb has a facing structure including a central shaving area 173 and marginal clipping areas 174 and 175 (Figs. 13 and 15). This face structure is formed of two face portions having the form shown in Fig. 16 including a side 176 and a top 177, the sides of each surface portion being provided with openings 178 for reception on the ends of the rivets 162, the sides being secured between the spacing sleeves and the outwardly disposed ends of the rivets, as best shown in Fig. 15, to form a rigid comb unit including the truss structure and the surface structure, which unit may be inserted in and removed from the shaver as a unit. The sides 176 are thus secured in approximate parallel relationship with the top portions 177 disposed inwardly. The top portions are of such width that the free edges 179 thereof abut in the area over the rib 168, and the space relationship is such that these edges are pressed firmly together to thus form the skin-engaging surface comprising the central area 173 and the marginal areas 174 and 175. At the junction between the side 176 and the top 177 the metal is curved outwardly as shown at 181 so as to overhang the sides. This area is provided with a plurality of U-shaped slot-like openings as shown at 182 disposed longitudinally of the top and providing longitudinally disposed teeth 183, the slots 182 and teeth 183 being analogous in form and function to the slots 83 and teeth 84 hereinbefore described. The top is also provided with

a plurality of slots 184 formed inwardly from the abutting edge 179 so as to provide a plurality of spaced teeth 185 spaced longitudinally of the comb. The slots 184 of the two surface structure portions may be so arranged that when the edges 179 are brought into engagement, the slots 184 of the two portions meet so as to produce a structure shown in Fig. 13. In Fig. 17 I have shown slots 184' of the two portions staggered so that the teeth 185' of one portion meet the slots 184' of the other portion. This has the advantage that when the shaver is moved over the skin, all parts of the skin between the end teeth of the central portion are covered by the slots with the consequent increase in the probability that all of the hair will enter the slots during a single pass of the shaver over the skin.

The comb is held in position in the shaver by means of screws 186 and 187 which pass through the tubular rivets 162 and 163 and are threaded into the plate 135. The cover 141 has openings, not shown, through which the heads of the screws 186 and 187 pass. The shaving ends of the housing portions 128 and 129 converge inwardly as shown at 188 and 189 (Fig. 12), so as to seat against the sides 176 of the comb to enclose the lower portions of the comb and prevent the access of hair to the interior of the motor chamber.

The cutter 174 reciprocates over the inner surface of the skin-engaging portion of the comb in the same manner as described for the cutter 116 and has a similar type of laterally floating action, permitting it to follow the curvature of this portion of the comb. The cutter is also provided with a slot 191 for reception of the central portion 169 of the rib and has a certain amount of freedom for lateral movement with respect thereto.

As in the previous embodiment the skin-engaging portion of the comb formed by the two top parts 171 is arched transversely of its length and longitudinally of its length as will be seen from a comparison of Figs. 14 and 15. In order to produce the desired characteristics in the skin-engaging portion of the comb, the tops of the surface structure are reduced in cross section in the central area 173. One satisfactory way of accomplishing this is to grind the comb on an arc of substantially greater radius than the transverse arc of the remainder of the comb portion, as for example, on an arc indicated by the line designated 192 in Fig. 15. By so doing the cross section of the central area 173 is reduced while the cross section of the marginal areas 174 and 175 is retained at its original thickness. It will be understood that the face structure of the comb is preferably formed from sheet metal of such thickness as to give rigidity thereto, and to give sufficient rigidity to the teeth 183 to prevent them from being bent out of shape in ordinary usage through mechanical damage. Preferably after the forming of these parts the metal is hardened so as to provide the desired edge holding properties and to cause it to withstand the abrasion occasioned by the action of the cutter.

The advantages of this form of the invention are similar to those heretofore described, and this embodiment has the further advantage that the comb is made up of fewer parts and is somewhat easier and cheaper to manufacture, the structure is somewhat lighter, and the comb may satisfactorily be produced in somewhat lesser widths than with the previously described structure.

In the embodiment of my invention as shown

in Figs. 18, 19 and 20, I form the entire comb unit of a single piece of sheet metal to a shape substantially as shown in the blank, Fig. 18. Here the shaving area is indicated by the dotted lines 193. Within this area the hair-receiving openings may be of any suitable or preferred size, shape or arrangement. However, in this species of my invention I prefer to employ two rows of narrow slots 194 substantially in herring-bone arrangement and adapted by reason of the shape to which they are subsequently formed, to provide for both close shaving and for snaring long hairs. The blank is then formed to the shape substantially as shown in Figs. 19 and 20. Here it will be observed that the skin-engaging portion 195 is arched both lengthwise and crosswise in keeping with the principle above described, but in this instance the crosswise arc is on a considerably smaller radius than in either of the previous forms. Also, the innermost edges 197 are bent laterally substantially along the line 198 to provide reinforcement for the side portions, although the general curvature of the comb both lengthwise and crosswise serves in itself to provide rigidity. The depending legs 199 serve for attaching the comb unit to the shaver housing or suitable supporting means substantially in the manner above described.

In Figs. 21 to 24 inclusive, I have shown another modification of my invention in which the comb unit is composed of a single strip of metal designated generally by 201 forming the skin-engaging part and truss structure designated generally by 202 which may be in keeping with any of the truss structures described. In this embodiment the comb member is provided with a centrally disposed close shaving area 203 having hair-receiving openings of the kind described for this purpose. On one or both of the longitudinal edges is formed a row of teeth 204 adapted for clipping long hairs. This comb member is formed and hardened substantially as above described to provide a double arched configuration, that is, the curvature lengthwise and crosswise. The comb member may be secured to the truss structure by any suitable or preferred means, such for example by riveting at the end portions beyond the close shaving area 203. In Fig. 21 is shown openings 205 in the comb member for the reception of rivet elements 205' formed on the top of the truss member 206 and adapted to enter the openings 205 and be peened or riveted over said member substantially as shown in Fig. 23. It will be observed that the rivet 205' is peened over only the outermost end of the opening 205 and in such manner as to hold the comb member 201 taut against the top of the truss member 206, as claimed in my application for shaving implement, Ser. No. 200,899.

As in some of the embodiments above described, the thin skin-engaging member is seated throughout the length of the shaving area or closely contiguous thereto against upper surfaces of the truss structure. In the previous instances, the comb supporting surfaces may be accurately finished as to curvature and the thin flexible comb is accurately conformed to the shape of these truss members. Here I have shown somewhat diagrammatically a cutter tool 207 and an oscillating carrier lever 208 in keeping with the principles above described. In this embodiment, however, I have provided stationary guard lips 209 disposed in coacting relation with the teeth 204, as shown in Fig. 23, and extending

the full length of the comb, as shown in Fig. 22, these guards serving with the comb member to guide the skin and prevent it from entering into contact with the cutter.

In view of the foregoing disclosure it will be manifest that various modifications may be made in the application of my invention without departing from the spirit and scope thereof, and I desire, therefore, that only such limitations should be placed thereon as are imposed by the prior art and the appended claims, in which I claim:

1. In a shaving implement, a comb comprising a skin-engaging member and a truss structure, the skin-engaging member being of a single piece of sheet metal having a central area provided with hair-receiving openings adapted for close shaving and a marginal edge provided with clipping teeth adapted for cutting long hair, the truss structure being shaped to support the skin-engaging member with its said central area and its said marginal edge in a form arched lengthwise and crosswise, and means securing the skin-engaging member to the truss structure with said member conforming to said arched form.

2. In a shaving implement, a thin metal comb of substantially greater length than width arched convexly both lengthwise and crosswise and having hair-receiving openings arranged centrally within the area of its longitudinally arched portion adapted for close shaving and a row of clipping teeth within the area of its said arched portion along one of its longitudinal edges adapted for cutting long hair.

3. In a shaving implement, a comb structure having two substantially identical side pieces each of sheet metal shaped to provide an upright side portion and an elongated top portion, the side and top portions joined by an outwardly projecting cyma curve portion, the inner marginal edges of the top portion being in contiguous relation to jointly provide a shaving area having hair-receiving openings adapted for close shaving, the outer marginal edges of the top portions having clipping teeth extending into open areas opening downwardly into the cyma curve portion, the top portions jointly providing the skin-engaging surface of the comb and being arched convexly lengthwise and crosswise of the comb.

4. In a shaving implement, a comb composed of two opposed members each of substantially identical construction, each member having an upper portion, an upright side portion, and a cyma curve portion joining said upper and side portions, the upper portions jointly providing a skin-engaging surface arched lengthwise and crosswise of the comb, hair-receiving openings in the central area of said skin-engaging surface adapted for close shaving, hair-receiving openings in the marginal area of said upper portion extending into said cyma curve portion, and clipping teeth in said marginal area extending into the second mentioned hair-receiving openings and having cutting edges at the inner side of the arched portion adapted for long hair cutting.

5. In a shaving implement, a comb structure having a central elongated piece of thin sheet metal provided with hair-receiving openings adapted for close shaving and having longitudinal side edges, and an elongated marginal piece of sheet metal of thicker section than the central piece positioned at each side thereof, each

5 10 15 20 25 30 35 40 45 50 55 60 65 70 75 marginal piece having a top portion contiguous to a longitudinal edge of the central piece and having an upright side portion, one of the top portions having outwardly extending clipping teeth adjacent to its side portion adapted for cutting long hair, the central piece and the top portion of each marginal piece providing a substantially continuous skin-engaging surface arched convexly lengthwise and crosswise of the comb.

6. In a shaving implement, a comb composed of a central member and two opposed side members, the central member having longitudinal side edges, each of said side members being of substantially identical construction, the central member being arched lengthwise and crosswise and provided with hair-receiving openings adapted for close shaving, each side member having an upper skin-engaging portion and an upright portion joined by a cyma curve portion, said upper portions being in juxtaposition to the outside longitudinal edges of the central member and being arched to conform with the lengthwise and crosswise curvature thereof, and hair-receiving openings in said upper skin-engaging portion opening into the cyma curve portion and being of a shape adapted for long hair cutting.

7. In a shaving implement, a comb structure having an area provided with hair-receiving openings adapted for close shaving and a marginal area adapted for clipping long hair, the latter area comprising a thin metal body having an upper skin-engaging portion and a lower side portion in angular relation joined by a cyma curve forming a projecting skin-engaging portion, and a row of U-shape openings intersecting said upper and said projecting skin-engaging portions and forming clipping teeth disposed in said upper portion each with its outer end projecting into the open end of its U-shape opening.

8. In a shaving implement, a thin comb member having a row of substantially U-shape openings each arranged to form a central tooth disposed between slot openings, the slot openings of each U-shape opening merging into its open end area and the intermediate tooth extending outwardly into said open area, and the imperforate portions between the U-shape openings forming guard members, the inner edges of the teeth and guard members constituting cutting edges, the comb member shaped in cross section to provide an upper skin-engaging portion and a lower side portion joined by a cyma curve forming a projecting skin-engaging portion and said row of openings being disposed with the open end area of each opening located substantially in said lower side and said cyma curve portions and with said slot openings extending upwardly into said upper portion.

9. The combination in a shaving implement, of a reciprocating cutter, and a comb held in shearing relation to the cutter, the comb having a central thin portion arched convexly lengthwise and crosswise and provided with hair-receiving openings in the arched area adapted for close shaving, and having an edge portion of heavier cross section conforming with said lengthwise and crosswise curvature provided with outwardly disposed clipping teeth adapted for cutting long hair.

10. The combination in a shaving implement, of a comb structure of substantially greater length than width, said comb structure having a skin-engaging area arched lengthwise and

crosswise, said area comprising a central elongated area of thin cross section extending lengthwise of the comb structure and marginal areas of greater cross section along its longitudinal side edges, a plurality of spaced hair-receiving openings in said central area adapted for close shaving and a plurality of spaced outwardly disposed teeth along said marginal areas adapted for clipping long hair, and a cutter having an arcuate comb-engaging face reciprocable in an arc corresponding with the lengthwise concave inner surface of the comb face in shearing relation to both said central and said side edge areas.

11. The combination in a shaving implement, of a reciprocable cutter and a comb in coacting relation, the comb comprising a skin-engaging structure having a central area of thin cross section provided with a plurality of spaced hair-receiving openings in shearing relation with the cutter adapted for close shaving and marginal areas of heavier cross section having outwardly disposed spaced teeth in shearing relation with the cutter adapted for clipping long hair, each marginal area being of formed sheet metal having a top portion and a depending side joined by a projecting cyma curve portion, said teeth being formed in said top portion and projecting into an open area in said cyma curve portion, said sheet metal marginal areas being separate parts removable from said central area, and means for securing said marginal parts in coacting relation with said central area.

12. The combination recited in claim 11 wherein said central area and said marginal areas are arched in directions at right angles to impart rigidity and close shaving properties thereto.

13. The combination in a shaving implement, of a reciprocable cutter and a comb in coacting relation, the comb comprising a skin-engaging structure having a central area of thin cross section provided with a plurality of spaced hair-receiving openings in shearing relation with the cutter adapted for close shaving and marginal areas of heavier cross section having outwardly disposed spaced teeth in shearing relation with the cutter adapted for clipping long hair, each marginal area and a portion of the central area being formed of a separate piece of sheet metal having a marginal top portion joining the said central portion and having a depending side joined to the marginal top portion by a projecting cyma curve portion, said teeth being formed in said marginal top portion and projecting into an open area in said cyma curve portion, and means for securing said sheet metal parts in coacting relation with each other and with the cutter.

14. The combination recited in claim 13, wherein said central area and said marginal areas are arched in directions at right angles to impart rigidity and close shaving properties thereto.

15. The combination in a shaving implement, of a comb structure comprising spaced marginal members each having a row of spaced outwardly disposed teeth, and a central member of substantially lesser thickness than said marginal members completely spanning the space between said marginal members and having a plurality of spaced hair-receiving openings adapted for close shaving, said marginal members and said

central member each being arched in two directions at right angles to jointly form a convex outer skin-engaging surface and a concave inner surface, and a cutter reciprocable over said inner surface in shearing relation to said teeth and said openings.

16. The combination in a shaving implement, of a comb structure comprising spaced marginal members each having a row of spaced outwardly disposed clipping teeth, and a central member of substantially lesser thickness than said marginal members completely spanning the space between said marginal members and abutting thereagainst and having a plurality of spaced hair-receiving openings for shaving, said marginal members and said central member being arched in two directions at right angles to jointly form a convex outer skin-engaging surface and a concave inner surface, and means disposed at the abutting edges of said marginal members and said central member for supporting said members, and a cutter reciprocable over said inner surface in shearing relation to said teeth and said openings.

17. The combination in a shaving device of a comb comprising a truss structure and a skin-engaging structure therefor, said truss structure comprising inter-connected ribs, said skin-engaging structure comprising a central strip of thin section material having a plurality of spaced hair-receiving openings adapted for close shaving, means for drawing the strip taut over said ribs, at least one marginal member extending along an edge of said central strip and having clipping teeth spaced longitudinally thereof, means for maintaining said marginal member in abutting relationship with the edge of said central strip and in contact with said truss structure, and a cutter reciprocable over the inner surface of said skin-engaging structure in shearing relation to said teeth and said opening.

18. In a shaving implement, a comb unit comprising spaced hollow supporting members, a plurality of truss members supported on said hollow members, spacer elements on the hollow members maintaining the truss members in spaced relation, and a skin-engaging comb structure of thin metal having an area arched convexly lengthwise and crosswise and having hair-receiving openings in its arched area, said truss structure being shaped to engage the concave side of the skin-engaging structure for supporting the same in said arched form, and means securing the skin-engaging structure in position on said truss structure.

19. The combination in a shaving implement, of a comb of substantially rectangular outline arched lengthwise and crosswise, the central lengthwise extending arched portion having a plurality of spaced hair-receiving openings providing shaving edges for close shaving, a longitudinal side edge of the arched portion being provided with outwardly disposed teeth for clipping long hair, a cutter having an arcuate comb engaging edge conforming in shape to the inner side of the arched comb in shearing relation to both said close shaving shearing edges and said clipping teeth, and means for oscillating said cutter in an arc corresponding with the lengthwise concave inner surface of the comb.

JOHN BRUECKER.
